UNITED STATES PATENT OFFICE.

ALFRED H. HUMPHREY, OF KALAMAZOO, MICHIGAN.

DESIGN FOR A LAMP.

SPECIFICATION forming part of Design No. 36,976, dated June 14, 1904.

Application filed May 6, 1904. Serial No. 206,784. Term of patent 7 years.

To all whom it may concern:

Be it known that I, ALFRED H. HUMPHREY, a citizen of the United States, residing at the city of Kalamazoo, in the county of Kalamazoo, and State of Michigan, have invented a new, original, and ornamental Design for Lamps.

My new, original, and ornamental design for lamps is clearly illustrated in the accompanying drawing, which is a side elevation view thereof.

What I claim as new, and desire to secure by Letters Patent, is—

The ornamental design for lamp, substantially as shown.

ALFRED H. HUMPHREY.
